UNITED STATES PATENT OFFICE.

JAMES E. SULLIVAN, OF DENVER, COLORADO.

PIPE-THREADING MACHINE.

1,099,215.

Specification of Letters Patent.

Patented June 9, 1914.

Application filed September 12, 1912. Serial No. 720,078.

To all whom it may concern:

Be it known that I, JAMES E. SULLIVAN, a citizen of the United States, residing at Denver, in the county of Denver and State of Colorado, have invented a new and useful Pipe-THREADING Machine, of which the following is a specification.

One object of the present invention is to provide novel means for gripping a pipe 10 while the same is being threaded.

Another object of the invention is to provide a novel form of mechanism for advancing opposed cutters toward each other to fashion a tapered thread upon the pipe.

15 A further object of the invention is to provide novel means for actuating said mechanism, from the element whereby the cutters are rotated to fashion the thread.

With the foregoing and other objects in view, which will appear as the description proceeds, the invention resides in the combination and arrangement of parts and in the details of construction hereinafter described and claimed, it being understood 25 that changes in the precise embodiment of invention herein disclosed can be made within the scope of what is claimed without departing from the spirit of the invention.

In the drawings,—Figure 1 shows the invention in longitudinal section; Fig. 2 is an end elevation of the pipe-holding means; Fig. 3 is a section on the line 3—3 of Fig. 1; Fig. 4 is a section on the line 4—4 of Fig. 1; Fig. 5 is a perspective of the pawl whereby 30 motion is transmitted to the means for cutting the tapered thread; and Figs. 6, 7 and 8 are side elevations of ratchet wheels which may be employed interchangeably in connection with the pawl shown in Fig. 5.

40 Referring to Fig. 1 of the drawings, that end of the machine to which the reference character A is applied will be considered the forward end, that end of the machine to which the reference character B is applied 45 being considered the rear end, descriptive terms being selected accordingly.

In carrying out the invention there is provided a spindle 1, about which is disposed a sleeve 2, having at its forward end a head 3, the rear face of which is cone-shaped as indicated at 4, the head 3 being provided with wrench faces 5. Outstanding from the sleeve 2 is a primary annular rib 6 provided with radial slots 7. Outstanding from the 55 sleeve 2 and disposed to the rear of the primary annular rib 6 is a secondary rib 8, pro-

vided with radial slots 9, alined longitudinally of the spindle 1 with the slots 7 of the primary annular rib 6. To the rear of the secondary ring 8 is located an auxiliary ring 10 which is devoid of slots and is slideable longitudinally of the sleeve 2. At its rear end, the sleeve 2 is threaded as indicated at 11 to engage with the interior of a nut 12, the spindle 1 terminating at its rear end in a reduced, threaded portion 14 engaged with the rear end wall 14^a of the sleeve 2. Surrounding the rear end of the sleeve 2 and abutting against the nut 12 is a cone 15.

The invention further includes a series of 70 pipe grips 16, preferably taking the form of flat plates, the pipe grips 16 being provided with beveled ends 17 adapted to be engaged by the cone face 4 of the head 3 and by the cone 15. The pipe grips 16 are located in 75 the slots 7 and 9 of the ribs 6 and 8, respectively, the pipe grips 16 being provided in their inner edges with notches 18 which receive the auxiliary ring 10. All of the grips 16 are connected by the ring 10 for simultaneous movement. In the outer edges of 80 the pipe grips 16 there are notches 52, alined transversely of the device, and in these notches 52 is located a spring band 19, the function of which is to draw the pipe 85 grips yieldingly toward the axis of the spindle 1 and to maintain the pipe grips in the slots 7 and 9 of the ribs 6 and 8, respectively.

The forward extremity of the spindle 1 is 90 reduced and threaded as indicated at 20 and mounted upon the threaded end 20 is a nut 21 and an abutment 21^a, spaced apart. The threaded end 20 carries a crank 22, held in place by a nut 23.

95 Journaled upon the threaded end 20 between the nut 21 and the abutment 21^a is a ratchet wheel 24. A means is provided for actuating the ratchet wheel 24, this means comprising a lever 25 which is mounted 100 upon the nut 21 to swing thereon with the nut as a fulcrum. In the rear face of the lever 25 there is a recess 26 covered by a plate 27. Mounted in the plate 27 and extended across the recess 26 is a pivot element 28 carrying a pawl 29 constrained by a spring 30 which is located in the recess 26, to engage with the toothed periphery of the ratchet wheel 24. The ratchet wheel 24 carries, adjacent its periphery, a pair of oppositely disposed, rearwardly projecting tool posts 31 provided with guides 32 in which 105 110

reciprocate studs 33 carrying back plates 34 provided with yokes 35 into which are threaded set screws 36 adapted to hold the cutting tools 37. One stud 33 of each pair 5 carries a tubular bearing 38 into which is threaded a lead screw 39, the lead screw 39 being rotatable in the tool posts 31. The lead screw 39 is right-hand threaded into one bearing 38 and is left-hand threaded 10 into the other bearing 38, so that when the lead screw 39 is rotated, the backing plates 34 and the tools 37 will be advanced toward each other and retracted from each other, depending upon the direction of rotation 15 imparted to the lead screw 39. In its intermediate portion, the lead screw 39 is reduced in diameter as shown at 40 so as to engage against longitudinal movement with the spindle 1, as will be understood best when 20 Fig. 2 is examined. The lead screw 39 is equipped adjacent its ends with abutments 41 receiving ratchet wheels 42 held in place by means of hand wheels 43.

A means is provided whereby rotatory 25 motion may be imparted to one of the ratchet wheels 42 and consequently to the lead screw 39. This means includes a pawl shown in clearest outline in Fig. 5 and denoted by the numeral 44, the pawl 44 having 30 upon one edge a rectangularly disposed lug 45 adapted to engage one edge of the lever 25, the pawl being provided with a finger 46 which projects beyond one end face of the pawl, the finger 46 outstanding beyond one 35 side face of the pawl. A pivot element 47 unites the pawl 44 movably with the lever 25. A retractile spring 48, preferably of helical form, is united with the pawl 44, intermediate the ends of the pawl, one end 40 of the spring being secured to the lever 25, as shown to best advantage in Fig. 4. The spring 48 when positioned as shown in Fig. 4, serves to hold the lug 45 engaged with one edge of the lever 25, the lug constituting 45 means for limiting the movement of the pawl under the action of the spring 48. The pawl 44 may be rotated upon its pivotal mounting 47 until the spring 48 swings across the pivot 47, whereupon the lug 45 50 will engage again with the edge of the lever 25, as shown in dotted lines in Fig. 4. When the pawl 44 is positioned as shown in solid line in Fig. 4, the pawl is adapted to engage with the ratchet wheel 42, but when 55 the pawl is positioned as shown in dotted lines in Fig. 4, the lever 25 may be swung upon its fulcrum without causing the pawl 44 to actuate the ratchet wheel 42.

If desired, the ratchet wheel 42 may be 60 replaced by other ratchet wheels 49, 50 and 51, shown respectively in Figs. 6, 7 and 8.

Operation: The pipe which is to be threaded is indicated in dotted lines in Fig. 1, and under one method of operation, the 65 pipe is gripped in a vise or other holding

structure. A wrench may be applied to the wrench faces 5 of the head 3 of the sleeve 2, or the nut 12 may be rotated. Under either of the circumstances above referred to, the sleeve 2 will be moved longitudinally, 70 the inclined face 4 of the head upon the one hand, and the cone 15 upon the other hand, being thrust toward each other, to engage with the beveled ends 17 of the pipe grips 16. The pipe grips 16 will thus be forced 75 radially of the spindle 1 and outwardly, so as to grip and to center the spindle on the pipe. Since the pipe grips 16 are mounted to slide in the slots 7 of the primary rib 6 and in the slots 9 of the secondary rib 8, it will be seen that these ribs constitute guides to direct the radial, outward movement of the pipe grips 16. Because the notches 18 in the pipe grips 16 are engaged 80 with the auxiliary ring 10, the auxiliary ring 10 and the notches 18 constitute inter-engaging elements preventing the independent individual movement of the pipe grips 16 longitudinally of the sleeve 2. When the operation above outlined has been completed, the pipe will be centered with respect 85 to the spindle 2 and will be held upon the sleeve 2 securely.

The cutting tools 37 are rotated about the periphery of the pipe to effect a cutting of 90 the threads of the pipe. In carrying out this operation, the lever 25 is swung to and fro upon the nut 21 as a fulcrum. Under such circumstances, the pawl 29 which is pivotally carried by the lever 25 will engage 95 the toothed periphery of the ratchet wheel 24, imparting a rotation to the ratchet wheel. When the ratchet wheel is thus rotated, the tool posts 31 and the yokes 35 carrying the tools 37 will be rotated around 100 the pipe, causing the cutting of a thread in the pipe. During this cutting operation, the rotation of the ratchet wheel 24 will impart rotation to the spindle 1, the threaded end 14 of which, engaging the end wall 14a of the sleeve 2, will cause the spindle 1 to move longitudinally in the sleeve 2, thereby moving the cutting tools 37 and defining the pitch in the thread which is being 105 cut.

The crank 22, being connected with the ratchet wheel 24, is used to impart rapid movement to the pipe holding means to change the relative positions of said means and the pipe.

In order to cut a tapered thread upon the pipe, the pawl 44 may be swung from the dotted line position of Fig. 4 into the solid line position of Fig. 4. The finger 46 of the pawl will thereupon engage the ratchet 115 wheel 42, relative movement between the pawl 44 and the lever 25 being prevented by the engagement between the lug 45 of the pawl 44 and one edge of the lever. When the finger 46 of the pawl engages the 120 130

ratchet wheel 42, rotatory movement will be imparted to the lead screw 39, the lead screw 39 engaging the bearings 38 and causing the yokes 35 together with the tools 37 to move radially of the spindle 1, with the consequent result that the thread which is fashioned upon the pipe will be of tapered or conical form. When it is not desired to cut a tapered or conical thread upon the pipe, the pawl 44 may be positioned as shown in dotted line in Fig. 4. An adjustment of the cutting tools 37 with respect to the pipe may be effected manually by rotating the lead screw 39 through the medium of one or both of the hand wheels 43.

Having thus described the invention, what is claimed is;

1. In a device of the class described, a sleeve having a conical head, the sleeve having a slotted rib; pipe grips slidable in the rib; and a ring slidable on the sleeve, the grips having openings receiving the ring to prevent individual movement of the grips with respect to the sleeve; and a cone movable longitudinally of the sleeve, the grips having inclined edges engaging the head and the cone.

2. In a device of the class described, a shaft; pipe gripping means thereon; a member rotatable with the shaft as a center; a tool-holder slidable radially of the supporting structure; and a lead screw journaled in the rotatable member and threaded into the tool-holder, the lead screw being engaged with the shaft to prevent longitudinal movement of the lead screw.

3. In a device of the class described, a shaft; pipe-gripping means thereon; a member rotatable with the shaft as a center; a tool-holder slidable radially of the supporting structure; and a lead screw journaled in the rotatable member and threaded into the tool-holder, the lead screw extending transversely of the shaft and having a reduced, concaved portion, bearing against the outside of the shaft to prevent longitudinal movement of the lead screw on the shaft.

4. In a device of the class described, a supporting structure; pipe-gripping means adjustable longitudinally of the supporting structure; a member rotatable upon the supporting structure; a pair of tool-holders held upon the member to rotate therewith around the supporting structure and to slide upon the member radially of the supporting structure; a lead screw held for rotation in the supporting structure, the lead screw being right hand threaded into one tool-holder and being left-hand threaded into the other tool-holder; a device for rotating the member to cut the thread; means carried by said device for actuating the lead screw to impart a taper to the thread; and means for producing relative longitudinal movement between

the supporting structure and the gripping means to define the pitch of the thread.

5. In a device of the class described, a supporting structure; pipe-gripping means adjustable longitudinally of the supporting structure; a member rotatable upon the supporting structure; tool-holders held upon the member to rotate therewith around the supporting structure and to slide upon the member radially of the supporting structure; a lead screw rotatable in said member, the screw being right-hand threaded into one tool holder and being left-hand threaded into the other tool-holder; means for imparting rotatory movement to the member; means for imparting rotatory movement to the lead screw; and means for producing relative longitudinal movement between the supporting structure and the gripping means.

6. In a device of the class described, a supporting structure; pipe-gripping means adjustable longitudinally of the supporting structure; a member rotatable upon the supporting structure; tool-holders held upon the member to rotate therewith around the supporting structure and to slide upon the member radially of the supporting structure; a lever fulcrumed upon the supporting structure; means for operatively connecting the lever with the rotatable member; a lead screw mounted in the rotatable member, the lead screw being right-hand threaded into one tool-holder and being left-hand threaded into the other tool-holder; a ratchet wheel upon the lead screw; a pawl pivoted to the lever and adapted to engage the ratchet wheel; interengaging elements upon the pawl and upon the lever adapted to limit the movement of the pawl in one direction upon the lever; and means for producing relative longitudinal movement between the supporting structure and the gripping means.

7. In a device of the class described, a sleeve provided at one end with a conical head, the sleeve being provided with primary and secondary annular ribs and with a slideable auxiliary ring, the primary and secondary ribs having radial slots; pipe-grips mounted to slide in the slots, each grip having a notch engaging the auxiliary ring to prevent the individual longitudinal movement of the grips with respect to the sleeve, the grips having transverse openings; a pre-hensile spring engaged in the openings; a cone mounted upon the other end of the sleeve, the grips having inclined edges adapted to engage the head and the cone; a nut threaded upon the sleeve and adapted to engage the cone; a spindle located within the sleeve and having threaded engagement with the sleeve; means for rotating the spindle; and a pipe-cutter supported for rotation upon the spindle.

8. In a device of the class described, a supporting structure; pipe gripping means mov-

able longitudinally of the supporting structure; a member rotatable upon the supporting structure; a tool-holder held upon the member to rotate therewith around the supporting structure and to slide upon the member radially of the supporting structure; means for producing relative longitudinal movement between the supporting structure and the gripping means to define the pitch of the thread; and a lead screw threaded into the tool-holder, the lead screw and the supporting structure having interengaging

parts co-acting to hold the lead screw against longitudinal movement and to permit the screw to rotate upon the supporting structure. 15

In testimony that I claim the foregoing as my own, I have hereto affixed my signature in the presence of two witnesses.

JAMES E. SULLIVAN.
